UNITED STATES PATENT OFFICE.

ERNEST L. REYNOLDS, OF TULSA, OKLAHOMA.

OIL BURNER.

Application filed October 24, 1927. Serial No. 228,392.

My invention relates to improvements in oil burners.

In accordance with my invention, I provide a burner wherein the oil is preheated prior to its entrance into the combustion chamber. To accomplish this, an oil heating chamber surrounds the combustion chamber and is heated from the products of combustion therein. The oil supply pipe preferably extends over the burner and the oil is heated before it enters the heating chamber. I also provide means to properly mix the incoming vaporized oil and air, within the combustion chamber, for effecting a complete combustion of the fuel and the elimination of carbon deposits. I also provide a baffle element, preferably in the form of a spider, which covers the top of the burner, and retains the gases within the combustion chamber, a sufficient length of time, to effect their complete combustion.

In the accompanying drawings, forming a part of this specification, and in which like numerals are employed to designate like parts throughout the same,

25 Figure 1 is a perspective view of a burner embodying my invention,

Figure 2 is a horizontal transverse section taken on line 2—2 of Figure 3,

30 Figure 3 is a transverse vertical section taken on line 3—3 of Figure 2,

Figure 4 is a horizontal section taken on line 4—4 of Figure 3, and,

Figure 5 is a perspective view of the various elements constituting the burner.

35 In the drawings, wherein for the purpose of illustration is shown a preferred embodiment of my invention, the numeral 10 designates a preferably cylindrical casing, constituting the body portion of the burner. With-

40 in this casing is an inner wall 11, preferably circular in horizontal cross section, and forming with the casing 10 an annular oil heating chamber 12. Upon the inner side of the wall 11 is a combustion chamber 13. An annular

45 pocket 13' is formed in the wall 11 and serves to catch oil, to be used in starting the burner.

The top portion of the wall 11 preferably flares upwardly, as shown. The wall 11 is provided with any suitable number of inlet

50 openings 14, spaced from the bottom of the combustion chamber 13, as shown, and through which the vaporized oil passes into the combustion chamber 13 from the heating chamber 12. The numeral 15 designates an

55 oil supply pipe, leading into the oil heating chamber 12, as shown, and this supply pipe

has a horizontal portion 16, preferably passing diametrically over the burner. A drain plug 17 is preferably provided, and may be arranged opposite the outlet of the pipe 15. 60

The bottom of the combustion chamber 13 is open and is equipped with a horizontal flange 18, which supports a mixing device, including generally radial blades or wings 19, attached at their inner ends to a central tube 65 20, open at its top and bottom. The blades 19 are spirally twisted upon their longitudinal axes, and the upper edges of these blades are at about the same elevation as the inlet openings 14. The tube 20 extends above the blades 70 19 and the openings 14, for a substantial distance, as shown.

Arranged beneath the casing or body portion 10 is a preferably cylindrical air admitting casing or shell 21, receiving in its upper 75 open end a depending annular flange 22,

formed upon the shell 21. The shell 21 is provided in its periphery with air inlet openings 23, partly covered by the flange 22. The shell

21 is provided centrally thereof with an up- 80 standing cylindrical flange 24, providing a central air inlet opening. The opening of the flange 24 may be adjusted to any size by means

85 of a pivoted plate or valve 25, but the openings 23 have their uncovered portions of a fixed area. Any suitable means may be employed

to hold the shell 21 to the flange 22, and the body portion of the burner 10 may be supported by any suitable means.

I also provide a retarding or diffusing 90

spider element, mounted upon the top of the combustion chamber. This spider element comprises a central preferably circular plate

26, having a reduced central opening 27, in alinement with the center of the tube 20. Ra. 95

diating from the central plate 26 are the arms 28 of the spider, which are relatively wide, with openings 29 between them. These arms rest upon the casing or body portion 10 and are held in place by an upstanding annular 100 flange 30.

During the operation of the burner, a jet 105 of the flame which is hot, passes upwardly through the opening 27 and heats the pipe 16,

whereby the oil is somewhat heated before entering the annular heating chamber 12.

When the oil enters the heating chamber 12 it is further heated by the intense heat from the combustion chamber 13. Some of the oil is vaporized and is sprayed through the inlet

110 openings 14, and is there met by the air passing through the openings 23 and 24, and ris-

ing into the combustion chamber 13. This air engages with the spirally twisted blades 19, and while traveling generally upwardly is also deflected radially horizontally and outwardly, and a thorough mixture is effected with the gases passing through the openings 14, which gases are ignited as they enter the combustion chamber. The flame produced by the gases escaping from the openings 14, 10 impinge upon the upper end of the air tube 20 and rebound therefrom and become more or less diffused. The air escaping from the top of the tube 20 is heated to a high temperature, and secondary combustion occurs in the 15 combustion chamber near and above the tube 20 and twisted blades 19. The spider retards the escape of the flame and products of combustion, sufficiently, so that the secondary combustion may be complete. The flame escaping through the openings of the spider is 20 intensely hot and is of a generally white color, resembling the filament in an electric lamp.

It is to be understood that the form of my 25 invention, herewith shown and described, is to be taken as a preferred example of the same, and that various changes in the shape, size and arrangement of parts may be resorted to without departing from the spirit 30 of my invention, or the scope of the subjoined claims.

Having thus described my invention, I claim:

1. In an oil burner of the character described, a closed oil heating chamber having an inner passage to produce a combustion chamber which is surrounded by the closed oil heating chamber, said heating chamber having apertures in its inner wall, leading 35 into the combustion chamber, means to supply oil to the oil heating chamber, means whereby air is supplied to the bottom of the combustion chamber, and a mixing device, arranged within the combustion chamber.
2. In an oil burner of the character described, a closed oil heating chamber having an inner passage to produce a combustion chamber which is surrounded by the closed oil heating chamber, said heating chamber having apertures in its inner wall, leading 40 into the combustion chamber, means to supply oil to the oil heating chamber, means whereby air is supplied to the bottom of the combustion chamber, and a mixing device, arranged within the combustion chamber.
3. In an oil burner of the character described, an oil heating chamber constructed 45

to produce a combustion chamber surrounded by the same, and having apertures leading 60 into the combustion chamber, means to supply oil to the oil heating chamber, means whereby air may pass into the lower portion of the combustion chamber, and a mixing device arranged within the combustion chamber and including a tubular hub and blades radiating therefrom, the apertures being arranged in substantially the elevation of the upper edges of the blades and the tubular hub extending upwardly beyond such upper 70 edges.

4. In an oil burner of the character described, an oil heating chamber constructed to produce a combustion chamber surrounded by the same and having apertures upon its 75 inner side leading into the combustion chamber and also having means whereby air may pass into the lower portion of the combustion chamber, means to supply oil to the oil heating chamber, a mixing device arranged within the combustion chamber and including an upstanding tubular hub and blades radiating therefrom, said apertures being positioned in substantially the elevation of the upper edges of said blades and the tubular hub extending above said upper edges, and a covering spider arranged over the top of the combustion chamber and embodying a hub portion and spaced radiating arms.

5. In an oil burner of the character described, a hollow annular oil heating chamber surrounding a combustion chamber and provided upon its inner side with apertures which lead into the combustion chamber, means to supply oil to the oil heating chamber, an air supply chamber in communication with the bottom of the combustion chamber and having air inlet openings in its side wall and a central air inlet opening in its bottom, a mixing device within the combustion chamber including a centrally arranged vertical tubular hub and spirally twisted blades radiating therefrom, said apertures being arranged in substantially the elevation of the upper edges of the blades and the tubular hub 90 projecting above such upper edges whereby the flames passing from said apertures may impinge upon the upper end of the tubular hub, and a covering spider arranged over the combustion chamber and embodying a central hub portion having an aperture formed therein and spaced relatively wide 95 radiating arms.

In testimony whereof I affix my signature.

ERNEST L. REYNOLDS.
